DESIGN FOR A BROOCH OR SIMILAR ARTICLE

Bernard Bauer and Ernest Steiner, New York,
N. Y.

Application March 8, 1938, Serial No. 75,668

Term of patent 3½ years

To all whom it may concern:

Be it known that we, Bernard Bauer and Ernest Steiner, citizens of the United States and residents of New York in the counties of Queens and New York, respectively, and State of New York, have invented a new, original, and ornamental Design for a Brooch or Similar Article of which the following is a specification, reference being had to the accompanying drawing, forming part thereof, and in which

Fig. 1 is a front view of a brooch or similar article showing my new design, and

Fig. 2 is an edge view thereof.

The leading distinctive feature of the design is the deer positioned with its head turned backwardly, framed within a background containing a leafy arrangement.

We claim:

The ornamental design for a brooch or similar article substantially as shown and described.

BERNARD BAUER.
ERNEST STEINER.
